UNITED STATES PATENT OFFICE.

WILMUR W. BOA AND KARL SCHOENBAUER, OF GRAND RAPIDS, MICHIGAN.

STARTING DEVICE FOR EXPLOSION-ENGINES.

1,035,150.

Specification of Letters Patent. Patented Aug. 13, 1912.

Application filed May 15, 1911. Serial No. 627,232.

To all whom it may concern:

Be it known that we, WILMUR W. BOA and KARL SCHOENBAUER, citizens of Canada, British America, and Germany, respectively, residing at Grand Rapids, county of Kent, State of Michigan, have invented certain new and useful Improvements in Starting Devices for Explosion-Engines, of which the following is a specification.

10 This invention relates to improvements in starting devices for explosion engines.

The main objects of this invention are, first, to provide an improved starting device or crank for explosion engines in which the 15 crank is quickly and positively disengaged in the event of "back firing." Second, to provide an improved starting device or crank for explosion engines which is simple and effective in structure and one in which the 20 crank is automatically disengaged in the event of the engine "back firing." Third, to provide an improved starting device or crank for explosion engines in which the parts are so constructed and arranged that 25 they are not likely to get out of repair or become inoperative through use or the jar to which the device is subjected when mounted on an automobile.

Further objects, and objects relating to 30 structural details, will definitely appear from the detailed description to follow.

We accomplish the objects of our invention by the devices and means described in the following specification.

35 The invention is clearly defined and pointed out in the claims.

A structure which is a preferred embodiment of our invention is clearly illustrated in the accompanying drawing, forming a 40 part of this invention, in which:

Figure I is a detail view, partially in longitudinal section, of a structure embodying the features of our invention, the crank and engine shaft clutch members being shown in 45 their engaging position. Fig. II is a similar view, additional parts being shown in section with the crank and engine shaft clutch members disengaged. Fig. III is a transverse section taken on a line corresponding 50 to line 3—3 of Fig. II. Fig. IV is a horizontal section taken in a line corresponding to line 4—4 of Fig. III through one of the pawls. Fig. V is an end view of the crank clutch member.

55 In the drawing, similar reference characters refer to similar parts throughout the

several views, and the sectional views are taken looking in the direction of the little arrows at the end of the section lines.

Referring to the drawing, 1 represents the 60 engine shaft and 2 is the shaft for the crank 3. The casing 4 is adapted to be mounted on an automobile body and is provided with a bearing 5 for the engine shaft 1. The casing cap is provided with a bearing 7 for the 65 crank shaft 2. On the inner end of the engine shaft is a jaw clutch member 8, a coacting jaw clutch 9 being mounted on the shaft 2. These clutch members are preferably 70 provided with spiral jaw faces, as shown in the drawing.

A cylindrical release member 10 is arranged within the casing to embrace the clutch members 8 and 9. The bearing 5 for the shaft 1 projects into the casing and 75 serves as a bearing for the release member. The release member is shouldered at 11 to engage the clutch member 8, and is held in position on its bearing thereby.

The crank clutch member 9 is provided 80 with radially disposed release member jaws 12, the release member being provided at its outer end with coacting notch-like jaws 13. The rear faces of the jaws 12 and the coacting jaws 13 are inclined rearwardly, as 85 shown in Fig. I so that when the release member is held against rotation and the crank is rotated rearwardly, the crank shaft is moved longitudinally to disengage the jaw members 8 and 9. The cap 6 limits the 90 outward movement of the crank. Projections 23 at the forward edges of the jaws 13 prevents the forward rotation of the crank without the rotation of the release member and guides the jaws when the shaft jaws are 95 being engaged.

The release member is driven with the crank on its forward rotation, and its rearward movement is prevented by the pawls 14, which coact with the peripheral ratchet 100 15 at the inner end of the release member. The teeth of this ratchet are preferably 105 square faced, while the rear sides of the pawls are beveled at 16. The pawls are so disposed that they engage alternately, one or the other of the pawls being in engagement at all times. This prevents any rearward movement of the release member so that in the event of a "kick-back" the release member immediately acts on the crank, shifting it to disengage the shaft clutch. 110 This is accomplished with a very slight rear-

ward movement of the engine shaft so that it is quite impossible for the crank to injure a person manipulating the same. In certain devices of this character, designed to release 5 on the "kick-back" of the engine, considerable movement is necessary before the release is effected, and while such a structure is of some advantage, it does not entirely eliminate the element of danger.

- 10 The pawls 14 are arranged in radial seats 17 provided therefor in the casings, the pawls being square or otherwise suitably shaped to prevent their rotation. The pawls are yieldingly supported by means of 15 the springs 18, the springs being retained by the plug 19 and the cap 20. The plug is provided for the upper pawl seat so as to leave a substantially flat surface for the attaching bracket 21. A set screw 22 is provided for the crank when not in use, it being desirable for preventing accidental engagement of the crank and also to prevent its oscillation and consequent wear.

Our improved starting device or crank is 25 very simple and compact in structure, and is, at the same time, a very strong and effective device, and one which is not likely to get out of repair. The clutches are disengaged so quickly on the "back firing" of 30 the engine that the element of danger is eliminated. The device may be easily applied to various types of starting shafts now in use.

Having thus described our invention, 35 what we claim is new and desire to secure by Letters Patent is:

1. In a starting device, the combination of the engine shaft; a crank shaft; coacting jaw clutch members for said shafts, the 40 crank shaft clutch member being also provided with radially projecting release jaws; a casing provided with a bearing for said engine shaft, the bearing projecting into said casing; an end cap for said casing provided with a bearing for said crank shaft, said crank shaft being longitudinally movable in its said bearing for the engagement and disengagement of the said shaft clutch

members; a cylindrical release member having a peripheral ratchet at its inner end and 50 notch-like jaws at its outer end coacting with the said release jaws, the rear faces of said release jaws being inclined rearwardly, said release member being mounted on said inwardly projecting engine shaft bearing 55 to embrace said shaft clutch members; and a pair of pawls, and bearing seats therefor arranged in said casing radially of said release member, said pawls being arranged to engage alternately so that said release member is continuously engaged by one or the other of said pawls.

2. In a starting device, the combination of the engine shaft; a crank shaft; coacting jaw clutch members for said shafts, the 60 crank shaft clutch member being also provided with radially projecting release jaws; a casing provided with a bearing for said engine shaft, the bearing projecting into said casing; an end cap for said casing provided with a bearing for said crank shaft, 70 said crank shaft being longitudinally movable in its said bearing for the engagement and disengagement of the said shaft clutch members; a cylindrical release member having a ratchet at its inner end and notch-like jaws at its outer end coacting with the said release jaws, the rear faces of said release 75 jaws being inclined rearwardly, said release member being mounted on said inwardly projecting engine shaft bearing to embrace said engine shaft clutch member and being adapted to receive said crank shaft clutch member and to coact with said crank shaft bearing in supporting the crank shaft when 80 the clutches are engaged, and a pawl for said release member ratchet mounted in said casing.

In witness whereof, we have hereunto set our hands and seals in the presence of two 90 witnesses.
